UNITED STATES PATENT OFFICE.

HUGO C. RASSMANN, OF BEAVER DAM, WISCONSIN, ASSIGNOR TO F. RASSMANN MANUFACTURING COMPANY, OF BEAVER DAM, WISCONSIN.

OVERHEAD TRACK.

1,323,722.

Specification of Letters Patent.

Patented Dec. 2, 1919.

Application filed April 9, 1919. Serial No. 238,665.

To all whom it may concern:

Be it known that I, HUGO C. RASSMANN, a citizen of the United States, and a resident of Beaver Dam, in the county of Dodge and State of Wisconsin, have invented certain new and useful Improvements in Overhead Tracks; and I do hereby declare the following to be a full, clear, and exact description of the invention, such as will enable others skilled in the art to which it appertains to make and use the same.

This invention relates to improvements in overhead tracks and more particularly to means for connecting a rod or flexible track with a rigid track.

In the construction of trackways such as are employed for litter and feed carriers, a rigid track is employed in the barn and a rod or flexible track is connected with the rigid track to any desired point outside of the barn. It is customary to secure the flexible track at both ends and it therefore extends in a straight line from its connection in the barn to its exterior connection and for this reason the rigid track in the barn approaches the rod or flexible track at an angle at the point of connection with the latter so as to allow the connecting device to lie on the rod track and also enable the hangers to be properly placed. The rod track does not always approach the rigid track from the same angle and for this reason it has been necessary to provide at least two forms of connectors,—one being designated "right-hand" and the other "left-hand", and in supplying such connectors, it has been necessary for a customer to specify which type he requires.

It is one object of my invention to provide a connector between the rigid and flexible tracks which can be readily adjusted to accommodate the flexible track regardless of the angle at which it may approach the rigid track.

With this and other objects in view, the invention consists in certain novel features of construction as hereinafter set forth and pointed out in the claims.

In the accompanying drawings; Figure 1 is a plan view illustrating my improvements; Fig. 2 is a separate view of the connector; Fig. 3 is a perspective view of the connector; Fig. 4 is a section on the line 4—4 of Fig. 2; Fig. 5 is a section on the line 5—5 of Fig. 2, and Figs. 6 and 7 are views illustrating

another application of my improved tip or connector.

1 represents a portion of a rigid track; 2 a portion of a rod or flexible track, and 3 my improved connector for the two tracks. 60

The rear portion of the connector 3 is bifurcated to form two arms 4, 4 which receive the end of the rigid track 1 between them, and said arms are perforated for the passage of bolts 5 for securing the connector 65 to the rigid track.

The connector is made with a forwardly projecting portion 6 which overlies the flexible track 2 and terminates at its free end with a tapering nose 7. The top of the connector forms a trackway 8 which alines at one end with the top of the rigid track and its forward portion curves downwardly to the flexible track at the nose 7. In rear of the nose 7, lugs 9 are provided which may be 70 bent to embrace the flexible track.

The connector is made, rearwardly of the lugs 9, with a reduced portion 10 for a purpose hereinafter explained, and in rear of said reduced portion, laterally and downwardly projecting lugs or ears 11, 11, are formed. The connector is made with a depending rib 12 which cooperates with the lugs or ears 11, 11 to form a frog. In practice, the flexible track 2 will pass between 80 the rib 12 and one of the lugs or ears 11, according to the angle at which said flexible track approaches the rigid track, and this portion of the flexible track may be secured to the connector by bending the adjacent lug 85 or ear 11 over the same.

In order that the connector may be adapted for use with a flexible track which may approach the rigid track at an angle, either from the right or left as indicated in Fig. 1, 95 the forward portion of the connector is made laterally adjustable. This may be accomplished by making the device of malleable or bendable metal and by forming the same with the reduced portion 10, so that the forward arm 6 of the device may be readily bent laterally to cause it to aline with the flexible track regardless of the angle of approach of the latter.

My improved connector or tip 3 may be 105 employed as part of a switch between two rigid tracks, such as a straight track 13 and a curved track 14, as illustrated in Figs. 6 and 7. When thus applied, the connector is secured to one end of a section 15 of rigid 110

track, and the other end of this track section 15 is connected with the end of the straight track 13 by means of a hinge 16—the track section 15 and connector 3 thus forming a switch. The hinging of the switch track section 15 to the straight track is such that the switch can be swung horizontally and the members of the hinge are so formed that the switch track can be raised to disengage the lugs of the connector from the curved track as shown by dotted lines in Fig. 7. When the connector rests upon the curved track the lugs 9 and one of the lugs 11 and also the rib 12 will engage the curved track and thus prevent lateral displacement of the switch. When the switch is thus set, a carrier can run from the curved track to the straight track. Should it be desired to cause the carrier to run only on the curved track, this may be accomplished by raising the switch section to disengage the lugs 9—11 and rib 12 from the curved track and then moving the switch section laterally as indicated by dotted lines in Fig. 6. The forward portion 6 of the connector may be bent or adjusted laterally in one direction to cause it to properly engage the track 14 when the latter curves as shown in Fig. 3, and said portion 6 of the connector may be bent or adjusted laterally in the other direction, when the track 14 curves in a direction opposite to that shown in Fig. 3.

Various slight changes might be made in the details of construction of my invention without departing from the spirit thereof or limiting its scope and hence I do not wish to restrict myself to the precise details herein set forth.

Having fully described my invention what I claim as new and desire to secure by Letters-Patent, is:—

1. A track connector having a rigid portion for connection with a track and having a horizontally bendable portion extending forwardly from said rigid portion and adapted to engage another track.
2. A track connector having a rigid portion adapted to be secured to a track and provided with a horizontally adjustable por-

tion adapted to engage another track, said connector having depending portions to be disposed adjacent to the last-mentioned track.

3. A connector adapted for connection with a rigid track and provided with a laterally adjustable forward portion adapted for attachment to a flexible track.

4. A connector adapted for connection with a rigid track provided with a laterally bendable forward portion adaptable for attachment to a flexible track.

5. A connector made of malleable metal and having a reduced portion between its ends, whereby the forward portion of the connector may be bent laterally.

6. A connector adapted for connection with a rigid track and provided with a laterally adjustable forward portion, said laterally adjustable portion provided with engaging means for a flexible track.

7. A connector adapted for connection with a rigid track and provided with a forward laterally adjustable portion adapted for attachment to a flexible track, and a frog in rear of said laterally adjustable portion.

8. A connector adapted for connection with a rigid track and provided with a laterally adjustable forward portion adapted for attachment to a flexible track, a depending rib in rear of said laterally adjustable portion, and lugs at respective sides of and spaced from said depending rib.

9. A connector made of malleable metal and having a reduced portion between its ends whereby the forward portion of the connector may be bent laterally, said forward portion having bendable lugs to engage a flexible track, a depending rib in rear of said reduced portion, and bendable lugs near respective sides of said rib and adapted to engage the flexible track.

In testimony whereof, I have signed this specification in the presence of two subscribing witnesses.

HUGO C. RASSMANN.
